WATER WINGS

Filed June 22, 1931

Pando Blagoeff

INVENTOR.

BY

Charles A. Clark, M. E.
ATTORNEY.

UNITED STATES PATENT OFFICE

PANDO BLAGOEFF, OF BROOKLYN, NEW YORK

WATER WINGS

Application filed June 22, 1931. Serial No. 545,891.

My invention relates to water wings and refers more particularly to wings that are attachable to the feet of the user.

One object of my invention is to provide 5 a simple, inexpensive device that can be utilized to accelerate swimming.

Another object of my invention is to provide a framework adapted to be attached to the feet of the user, carrying two freely 10 pivoted elements that are movable within an angle of ninety degrees.

A further object of my invention is to provide a water wing comprised of a relatively 15 long rectangular element having a multiple of L shaped parts pivoted thereto.

A still further object of my invention is to provide simple wings attachable to the feet, for giving speed in swimming.

I attain these objects preferably by the 20 means illustrated in the accompanying drawings, wherein similar numerals refer to like parts throughout the several views, in which:—

Figure 1 is a plan of the device.

25 Figure 2 is a section taken on lines 2—2 of Figure 1.

Figure 3 is a side elevation of the device attached to the foot.

Figure 4 is a detail plan of one wing.

30 Figure 5 is a side elevation of wings attached to a shoe.

Figure 6 is an end elevation of wings attached to a shoe.

35 Figure 7 is an isometric view of one of the supports to which the wing shown in Figure 4 is pivoted.

The device shown in Figures 1 to 4, will consist of four wires 1, 2, 3 and 4, each bent as clearly shown in Figures 1, 2 and 3.

40 Referring to Figure 2, representing a side elevation of the wire 1, this wire is bent U shaped, curved at the bottom point 5, bent outwardly at 6 and 7, to provide a stop for the side elements or wings 8 and 9, and inwardly at the top where it is given a single turn 10 and 11, to provide means for holding pivot rods 12 and 13, and after making a turn, the wire is bent outwardly at 14 and 15, providing a stop for the wings 8 and 9, so that these

wings have a complete free movement of less than ninety degrees.

The wires 1, 2, 3 and 4, project downwardly in different and suitable distances, to fit the contour of a conventional foot 22, the 55 wires 1 and 4 being adjacent the ends of the wings 8 and 9, and the wires 2 and 3 spaced apart at the center thereof.

Between the wires 2 and 3, there is attached in any suitable manner, the tie strings 16 and 17, that pass around the ankle and are tied at 18, and if required, the tie strings 19 and 20 may also be attached, as clearly shown in Figure 3.

These wires may be provided with a rubber 65 or other suitable covering like 21, and the wing on the outside of the foot be wider than the inside one.

In Figures 1 and 3, inclusive, the device is shown as made up of two separate devices 70 adapted to be secured or suitably fastened to a shoe 23, preferably sewed thereto, as clearly shown in Figure 5.

The single unit device is comprised of a wing either like 8 or 9, depending upon which 75 side of the foot it is placed, and having three pivot supports like the one shown in Figure 7.

In Figure 7, the wire 24 is coiled at 25, bent at an angle less than ninety degrees at 26, and then bent back at 27.

These elements 24 are preferably secured 80 upon the side of the bathing shoe 23, as clearly shown in Figures 5 and 6, and the elements are pivoted to the wings by means of pivots like 12 and 13.

Having thus illustrated and described the preferred embodiment of my invention, I do not wish to limit myself to the exact construction or arrangement of parts shown, 85 since it is evident that modifications may be made therein, without departing from the spirit of the invention or scope of the claims.

I claim:—

1. A water wing comprised of two wings 90 and a multiple of U shaped wires bent and coiled on the sides to provide stops for wings attachable thereto by means of a pivot, said pivot engageable with said coils and wings.

2. A water wing comprised of two wings 95 with rolled edges and a multiple of U shaped 100

wires bent and coiled on the sides to provide stops at an angle less than ninety degrees for wings attachable thereto by means of a pivot, said pivot or pivots engageable with said coils and wings and a covering for said wires.

3. A water wing comprised of two wings with rolled edges and a multiple of U shaped wires bent and coiled on the sides to provide 10 steps at an angle less than ninety degrees, for wings attachable thereto by means of pivots, said pivots engageable with said coils and wings and a covering for said wires, said wings provided with openings providing a 15 means for attaching a holding tape to said pivots.

4. A water wing comprised of a wing with rolled edges on three sides and a tubular edge on the fourth side with openings therein, said 20 openings adapted to hold coiled wires bent at right angles and a pivot engageable with the said tubular portion and the coils.

5. A water wing attachable to a bathing shoe, comprised of a wing with rolled edges 25 on three sides and a tubular edge on the fourth side with openings therein, said openings adapted to hold coiled wires bent at right angles and one side having a return bend and a pivot engageable with the said 30 tubular portions and the coils.

Signed at New York in the county of New York and State of New York this the 17th day of June, 1931.

PANDO BLAGOEFF.
